UNITED STATES PATENT OFFICE.

SHEPHERD M. DUGGER, OF BANNER ELK, NORTH CAROLINA.

LEVEL.

1,116,577.

Specification of Letters Patent. Patented Nov. 10, 1914.

Application filed April 11, 1914. Serial No. 831,194.

To all whom it may concern:

Be it known that I, SHEPHERD M. DUGGER, a citizen of the United States, residing at Banner Elk, in the county of Avery and 5 State of North Carolina, have invented a new and useful Level, of which the following is a specification.

This invention relates to improvements in levels and more particularly to a level in 10 combination with a Jacob staff.

An object of the present invention is to provide an improved form of level which will possess an inherent ruggedness such as will render it adaptable and particularly 15 useful to miners and farmers.

A further object is to provide a plumb and needle level the readings of which are taken from the top surface so that the sight and scale readings can be taken substantially 20 simultaneously.

A further object is to provide a level and a Jacob staff for the supporting thereof and which Jacob staff is provided with means whereby the level may be raised and lowered 25 with precision such as is necessary and desirable with the taking of what is termed back sights.

With the foregoing and other objects in view which will appear as the description 30 proceeds, the invention resides in the combination and arrangement of parts and in the details of construction hereinafter described and claimed, it being understood that changes in the precise embodiment of the invention herein disclosed, can be made 35 within the scope of what is claimed, without departing from the spirit of the invention.

In the drawings accompanying this specification and forming a part thereof, the preferable form of my invention is illustrated, in which:

Figure 1 is a view in perspective illustrating my improved level and Jacob staff or stand therefor. Fig. 2 is a cross sectional view taken on a longitudinal line through the center of the staff and level proper. Fig. 3 is a plan view of the rotatable portion of the staff and illustrating the roller bearing whereby the friction is reduced to a minimum and a smooth operation or rotation of the device is procured. Fig. 4 is an end view in elevation of the level. Fig. 5 is a detail cross sectional view of the elevating means of the level.

Referring to the drawings in which similar reference numerals designate corresponding parts throughout the several views, the level proper comprises a two part body or casing 6 the separate sections of 60 which are held in rigid relation by the screws or other holding means 7. The central portion of the top is arcuated as at 8 and which is provided with the four scales 9 graduated thereon which read from a central zero line 10 as a reference.

Each section of the casing is provided with a slot or opening 11 which is provided with the restricted portion 12 adjacent the lower extremity thereof. The side walls of 70 the slot 11 are disposed at an angle to the vertical axis of the casing and are parallel to lines radiating from a point 13 as a center. Mention is here made of the fact that the level body or casing 6 is substantially 75 semi-cylindrical in outline, which allows the same to be supported in a rotatable manner and swing about a point or line 14 as a center which is approximately coincident with the longitudinal axis of a cylinder of 80 which the casing might be considered as a semi-portion. Rigidly secured to the opposite cylindrical surfaces of the casing are the sight plates 15, each of which is provided with the upstanding ears 16. The 85 sight plates rise above the upper surface of the casing so that the line of vision will not be intercepted by the inclinometer needle or any parts adjacent thereto. Also attention is called to the fact that the wide sight 90 plates allow sights to be taken even though the rod or pole upon which the sights are taken does not lie dead ahead of the instrument.

Extending through the restricted portion 95 of the slot 11 is the pivot 13' rotatably mounted upon which is the inclinometer needle 17 the lower extremity of which is enlarged to form the plumb portion 18. Secured to the upper extremity of the needle 100 and moving over the graduated scales 9 is the indicating arm 19. A forked rod 20 is provided with the screws 21 extending through the upper forked portions thereof, rotatably mounting the casing, and serving 105 as clamp screws to regulate the friction by which the casing rotates smoothly and is held at the desired adjustment. Rigidly secured to the lower extremity of the rod 20 and projecting therebeneath is the ball mem- 110

ber 22 which coacts with a socket 23 formed in the sliding member 24. As illustrated in Fig. 2 the lower extremity of the rod 20 and the upper and contacting surface of the member 24 are spherical in outline which provides for constant contact between the two surfaces and at the same time allows for the universal relative motion of the two parts.

10 A staff 25 is provided at its lower extremity with a point 26 which can be driven into the ground for the supporting and holding rigid of the instrument. The upper extremity is provided with a rotatable sleeve 27 journaled thereon, the lower extremity of which sleeve is provided with a number of teeth 28 which coact with the teeth 29 of the elevating member 30 which are cut in a spiral as well as helical manner. It is noted 15 in passing that the elevating member 30 is provided with a threaded extremity 31 engaging a threaded aperture 33 which extends transversely through the staff and provides that the elevating member will be 20 moved longitudinally as the same is rotated thus bringing the teeth 29 in engagement with the sleeve 28 with the simultaneous rotation and elevation of the latter. The simultaneousness of the two actions provides 25 for a smooth and accurate raising of the level. The under surface of the member 24 is provided with a number of roller bearings which provide for the anti-frictional 30 relative rotation of the member 24 and the sleeve 27 upon which it bears. The inner 35 surface of the sleeve 27 is threaded as at 32 which coacts with the external threads 33 of the staff. The pitch of the threads 32 is the same as the pitch of the spiral teeth 29. 40 Thus the teeth 28 and 29 will remain in constant engagement.

In order to prevent the member 24 from being turned as the sleeve 27 rotates, a square projection 34 is provided and which 45 slidably engages the side walls of a square aperture 35. Extending downwardly from the member 24 are the arms 36 provided with the inwardly extending knobs 37 at their lower extremities and which fit within 50 and engage a peripheral groove 38 cut upon the sleeve 27. The arms with the inwardly projecting knobs allow for the relative rotation of the sliding member and sleeve but prevent the longitudinal shifting thereof.

55 The many advantages accruing from a structure of this character will be readily appreciated especially by those who find usage for instruments of this character in the laying out of drains, the leveling of 60 terraces, foundations of buildings, and in connection with mine and surveying work where the instruments are called upon to withstand considerable hardship. Among the desirable features of the hereinbefore 65 described structure the following are men-

tioned. The scale being disposed upon the top of the instrument, allows the same to be read from above or from either side. The manner in which the inclinometer needle is mounted provides for the complete housing 70 thereof and protects the same from injury. The manner in which the inclinometer needle is mounted provides for a close precision in readings as the upper extremity of the needle moves to a greater distance for 75 equal movements of the plumb 18. The raising of the level is accomplished by a rotating of the elevating member 30 which by reason of the fact that it rotates and elevates the sleeve 27 at the same time, a 80 smooth and uniform raising of the level can be obtained in taking back sights. The square member 34 prevents the rotation of the member 24 but allows for the longitudinal movement thereof. 85

Having thus fully described the invention what I claim to be new and original with me is:—

1. A leveling instrument comprising a body portion provided with a slot extending transversely therethrough, an inclinometer needle pivotally mounted within said slot and extending through the top thereof, a staff provided with an upper forked end, and means for rotatably securing the body 95 to the said forked end of the staff.

2. In an instrument of the character described the combination of a body portion, an inclinometer needle housed therein and protected thereby, a rod rotatably supporting the said body portion, and a staff secured to said rod and provided for universal motion relative thereto, and means for preventing the separation thereof. 100

3. In an instrument of the character described the combination of a casing, an inclinometer needle pivotally disposed therein, a rod rotatably supporting said casing, a staff, a sleeve carried thereby, means for elevating and lowering said sleeve, and a 110 universal connection between the said forked rod and said sleeve.

4. In an instrument of the class described, the combination of a casing, provided with a slot extending therethrough with a restricted 115 lower portion, an inclinometer needle rotatably housed within said casing, the top surface of said casing upon opposite sides of said needle housing slot adapted to receive scales thereon, a forked rod rotatably carrying said casing, a ball member secured to and extending beyond the lower extremity of said forked rod, a sliding member provided with a socket therein for the receiving and universal mounting of the said 120 forked member, a staff, a non-rotating and sliding joint between said staff and said sliding member, a sleeve threadedly secured to and carried by the upper extremity of said staff, and means for rotating the said 125 130

sleeve for the elevating and lowering of said rotating member and the structures mounted thereabove.

5. In an instrument of the character set forth, the combination of a semi-circular casing, an inclinometer needle housed therein and rotatably supported thereby, sights secured upon opposite sides of said semi-circular casing, a rod rotatably mounting 10 the said semi-circular casing, a staff, and a universal connection between said staff and said rod, and means for raising and lowering said universal connection with respect to the said staff.
15. 6. In an instrument of the class described, the combination of a casing, a horizontally reading inclinometer needle carried thereby and housed therein, a rod rotatably mounting the said casing, a staff, a sleeve threaded 20 to the upper extremity thereof, said sleeve

provided with teeth formed along the lower extremity, an elevating member threadedly engaging the said staff and provided with a spiral helical portion with teeth upon the various convolutions thereof adapted to continuously engage the teeth of said sleeve for the rotating thereof, a member slidably and non-rotatably secured to said staff and bearing upon the said sleeve adapted to be elevated and lowered thereby, and a universal connection between the first mentioned rod and the last mentioned member.

In testimony that I claim the foregoing as my own, I have hereto affixed my signature in the presence of two witnesses.

SHEPHERD M. DUGGER.
